ATTORNEY.

UNITED STATES PATENT OFFICE

WILLIAM H. SCHMITT, OF ST. PAUL, MINNESOTA

WINDOW STAY AND FASTENER

Application filed January 8, 1931. Serial No. 507,420.

My invention relates to bracing means for holding a storm window or other pivotally suspended window rigidly and securely in non-rattling position either closed or open. The main object is to provide a simple, efficient and inexpensive device for said purpose and embodying certain hinge features and holding means designed to eliminate any rattling or other objectionable noise caused by the elements shaking a window particularly when it is in its outwardly directed position with its lower part in spaced relation to the window frame.

The construction and operation of my device are hereinafter fully set forth, reference being had to the accompanying drawing, in which,—

Figure 1 is a top or plan view of one of my devices in operative position holding the lower part of a storm window out, only a portion of the window stile and the storm window being shown.

Figure 2 is an elevation of Figure 1 omitting the window frame or stile.

Figure 3 is an enlarged sectional elevation taken vertically at the center of a window and looking toward its right hand vertical frame parts and including my improved brace means in position holding the storm window closed.

Figure 4 is an enlarged cross sectional view of the knee joint of my device as on line 4—4 in Figure 2.

Figure 5 is a top detail view of a certain preferred type of yieldable, corrugated spring-washer used in my device.

Figure 6 is a diametrical section of Figure 5 as on line 6—6 in the latter view.

Figure 7 is an enlarged inner face view of the knee joint end of the inner bar of my device.

Figure 8 is an enlarged detail end view, in perspective, of the other end of said bar.

Figure 9 is a perspective view of the stile plate of my device.

Figures 10 and 11 are both enlarged vertical sectional elevations of the stile plate, the former taken centrally as on line 10—10 in Figure 2 and the latter as on line 11—11

in said Figure 2 near and parallel to the inner flange of said plate.

Figure 12 is a perspective view of the brace.

Referring to the drawing by reference numerals, 15 designates either of the vertical stiles of a window frame having an outer depression 16 for retaining a storm window and the usual grooves 17 for slidably retaining the house window sash of which only the lower and inner one is shown and designated as 18, and between said depression 16 and the said grooves 17 the usual spacing strip 19. 20 designates either vertical side bar of a storm window suspended pivotally (not shown) from the upper part of the window frame by suitable hinge means.

My device comprises a storm window bracket preferably of plate metal and L-shaped in horizontal cross section, one flange of which, as 21F is fixed vertically to the inner face of a bar 20 as at 22 while its main plate 21P extends inwardly therefrom and is drilled for an outer joint bolt 23, the plate 21P being reduced inwardly of said joint and terminating in inwardly opening hook-shaped arm 21H having an aperture 21A near said hook for a purpose to be described.

24 is an outer leg section of my brace and 25 is an inner leg section preferably shorter than section 24 both pivotally connected by a bolt 26 and the outer section pivoted on bolt 23 of the bracket 21, while the inner end of section 25 is pivotally retained in a pivot plate 32 removably fixed in a stile-bracket 27 fixed as with screws 28 to the parting strip 19 of the window frame. Thus, is formed a knee joint at 26 and member 25 may further be provided with an integral extension forward of bolt 26 and having an inwardly directed lip 25L arranged to engage the top edge of member 24 when the two sections 24—25 are in alinement (see Figures 1 and 2 and 7). The legs 24—25 are preferably flat bar stock as shown and enlarged at their pivotally connected ends. In the adjacent faces of said ends I provide in each member a circular depression 33 and diametrically opposite notches 33N for receiving respectively a circular dished-flange spring metal

washer 34 having diametrically opposite tongues 34L. Each washer 34 is slotted radially from its bore, as 34S in Figure 5 and the face of the washer comprises radial corrugations 34C. There are two such washers on bolt 26 with their corrugated faces contacting and their tongues locked in the grooves 33N in the respective members 24-25. The bolt 26 is provided exteriorly of the joint with a castellated nut 29 held by a cotter pin 30 (see Figure 4). It is obvious that the washers 34 may be brought into frictional contact and their corrugated faces frictionally engaged as desired by setting nut 29 as tight as necessary, the spring metal washers 34 having a yielding tendency but also tending to keep the entire knee joint rigid regardless of the positions of the members 24 and 25.

Bolt 23 is similar to bolt 26 and has the 20 castellated nut 29, also adjustable. The outer or bracket joint on bolt 23 is assembled identical to the knee joint just described, having spring washers 34 about bolt 23 and squeezed between the outer end of member 24 and the 25 plate 21P, both the joints being aptly illustrated in Figure 4.

The inner end of leg member 25 comprises preferably two downwardly directed arms 25A formed arcuate as (Figure 8), with relation to the center of a pivot hole 31 in the end of the bar (see Figure 8) each said arm terminating in an outwardly directed flange 25F in parallel plane to the main part of the bar. The said arcuate arms 25A provide 35 bearing surfaces engaging in a round aperture 32A of a pivot plate 32 of quadrangular shape and preferably spring metal, and the flat extensions 25F engage under side of said plate while bar 25 bears lightly against or is 40 adjacent to the outer face of said pivot plate. The plate 32 is normally in vertical plane and has two opposite reduced flat ends or fingers 32F slidably and removably engaging in opposite slits 27S of a stile plate 27 45 of my device which will now be described. Said plate is a vertical quadrangular base of sheet metal and having the apertures 28 for wood screws or like fastening means. 27R is a rear flange on said plate and 27F is a 50 front flange at respective upright edges of the plate the former flange preferably the entire length of the plate and the latter extending upwardly and thence inwardly in a curvature from the central outer edge of 55 the plate and directed inwardly therefrom as best shown in Figures 2 and 9, said flange 27F being preferably arched in cross section and its outer curvature in the path of movement of the brace member 25 and engaged frictionally thereby as shown in Figure 1.

35 (Figures 9 and 10) is a fixed pivot pin in stile plate 27 and projecting outwardly enough to pivotally engage the aperture 31 of brace member 25, as best shown in Figure 10. 27S in Figures 9 and 12 shows elongated

slits wider at their diagonally opposite ends so that the pivot plate 32 can be centered on the pin 35 with its fingers in angular position (as shown dotted in Figure 2) after which the said pivot plate is swung to horizontal position, with its fingers, the latter thereby being forced simultaneously into the oppositely located narrow parts of the slits 27S and frictionally retained therein. Thus, the rear member 25 of my brace is pivotally secured in the plate 32 removably fixed in the stile plate 27. To obviate any accidental loosening of the pivot plate 32, I provide two spring tongues 27T struck up from the plate 27 one parallel to each flange, the free ends of such tongues being raised above the plane of said plate and located adjacent one edge of the finger piece 32F of the pivot plate to thus prevent edgewise slipping or loosening of the said pivot plate. To remove plate 32-32F it is only necessary to press the said tongue 27T down until the part or parts 32F can be slipped over and past it.

In Figure 3 is clearly shown how the device, at one side of a window, is folded up into a small space when the storm window is closed, this figure also showing a flat spring metal hook bar 37 fixed to the inner central part of the lower bar of the storm window and extending thence inwardly and curved upwardly as 37C to form a finger hook or catch. Near said hook 37C is an aperture 37A to be occupied by a projection 38P of a plate 38 fixed on the window lintel in the path of said hook so that the latter will frictionally engage and spring over the projection until the apertured part catches thereon as the storm window is closed.

In Figures 1, 2, 9 and 12, 27R' is an outwardly projecting extension of the lower part of flange 27R. This projection is in such a position that when the storm window is closed the finger piece or catch 21H rides on this projection being sprung inwardly until the aperture 21A is alined with the projection 27R' at which time the arm 21H of course snaps into locking position with 27R' to release the device from the closed position. The spring arms 21H are simply sprung inwardly and out of contact with the projections 27R' and the storm window is then free to be pushed outwardly to its open position. The auxiliary hook member 37 previously described is not necessary where the locking arms 21H are used. It is obvious that the latching spring 37 is most necessary when the latching means above described are not made as in part of the window bracket 21.

The use of my improved storm window bracket has been quite fully disclosed in the preceding specification; it might be stated further, however, that the joint construction as on bolts 26 and 23 together with the corrugated spring washers and the adjustments provide for positive elimination of objec-

tionable noises such as occurs where bolts become loose and by wearing the adjoining parts in such a manner that there is a rattling noise caused when the window is shaken by the wind. The advantages of these joint constructions is very clear but the use of my device is further augmented by the bearing flange 27F frictionally engaged by the bar 25. The removable part 32 is also a feature as the stile plate 27 is left on the window frame and the other bracket parts are readily folded up against the side members of the storm window for storage purposes.

I claim:

15. 1. A foldable stay and fastener for a pivotally suspended window sash, said fastener comprising a window bracket fixed to the window near its lower free end, a stile bracket fixed on the window frame, a collapsible knee joint member connecting said brackets and comprising two bars pivotally connected together, one of said bars, the outer bar, pivotally connected to the window bracket and the other bar, the inner bar, pivotally and removably connected to the stile bracket, adjustable and yieldable friction means in the pivot connection of said outer bar and the window bracket, and yieldable, adjustable friction means between the bars 30 at their pivotal connection forming the knee joint.

2. The structure specified in claim 1 and a lateral extension of one of said bars at its connection with the other bar and a transverse integral finger on the said extension arranged to engage the adjacent edge of the other bar to limit the straightening movement of both bars when the lower part of the window is swung outwardly from its frame.

40. 3. The structure specified in claim 1, in which said adjustable friction means at the knee joint pivot and the pivot connection to the window bracket, comprises for each joint, a pair of shallow circular washers each with a radially corrugated face, said washers placed face to face, a bolt passed through the pivoted parts and said washers placed between said parts and key means provided on each washer and in each of said joined parts for preventing rotation of the washer with relation to the part to which it is keyed, an adjusting nut threaded on one end of said bolt for clamping the said joint means together as tight as desired and means for holding said nut from rotating on the bolt.

45. 4. The structure specified in claim 1 in which said removable inner bar end means comprises a pivot plate with reduced opposite ends, said plate provided with a central aperture, the inner end of said inner bracket bar comprising a pair of integral arms arranged to be passed through said aperture and engage therein pivotally and the extremities of said arms adapted to be bent out-

wardly from the center of the bar to bear against the under side of said pivot plate, said pivot plate having elongated flanges one at each of its vertical edges and both provided with slits adapted to be frictionally engaged by the reduced ends of said pivot plate simultaneously and spring means in said stile plate arranged to hold said reduced ends of the pivot plate in the position described.

5. The structure specified in claim 1, and a fixed center pin in said stile plate, said inner bar having an aperture arranged to be loosely journaled on said pin, and means engaging said latter inner bar end to hold it in pivotal position on said pin.

6. The structure specified in claim 1 in which said brace bars are normally foldable upward only at the knee joint, and normally in upright parallel planes when the window is closed, said yieldable tension means on the stile bracket comprising a rolled flange at the upper and outer edge part of the stile bracket and arched inwardly toward the top of the latter, the inner of said bars being nearest to said rolled edge and arranged to frictionally engage said arched flange when said bar is swung outwardly on its pivot, as shown and for the purpose described.

7. An adjustable joint for a foldable window stay and fastener comprising, a pair of pivotally connected members, adjustable friction means disposed between said members upon the pivot, said friction means including a pair of slotted dished washers, the faces of said washers being radially serrated and in mutual contact, means including lugs for securing each washer to its adjacent member, and means to hold said members and friction means in adjusted position.

8. An adjustable joint for a foldable window stay and fastener comprising, a pair of pivotally connected members, adjustable friction means disposed between said members upon the pivot, said friction means including a pair of slotted spring washers, the contacting faces of said washers being corrugated, means holding said washers against rotation, and means to hold said members and friction means in adjusted contacting relation.
